Carlos P. Griffin

ATTORNEY.

UNITED STATES PATENT OFFICE.

OSCAR C. GOERIZ, OF OAKLAND, CALIFORNIA.

WATER-TURBINE DRAFT TUBE.

Application filed October 18, 1922. Serial No. 595,435.

To all whom it may concern:

Be it known that I, OSCAR C. GOERIZ, a citizen of Germany, residing at Oakland, in the county of Alameda, State of California,

5 have invented a new and useful Water-Turbine Draft Tube, of which the following is a specification in such full and clear terms as will enable those skilled in the art to construct and use the same.

10 This invention relates to draft tubes used in connection with reaction turbine wheels and its object is to reduce the discharge velocity of the water and to avoid the necessity of making the deep excavations necessary 15 with the ordinary form of straight draft tubes.

The modern high speed turbine discharges the water with such a high residual velocity that the most efficient draft tube design 20 is required to reduce that velocity to as low a velocity as possible to give the most efficient results for a given quantity of water used. This design would cause the straight draft tube to become so long as to produce 25 excavations of prohibitive depths.

The present invention provides a downward flow draft tube combined with an air tight water sealed chamber above the tail water level. The chamber is arranged so 30 it will receive part of the water issuing from the tube, but all of the water will eventually be discharged at or below the tail water level.

Another object of the invention is to provide 35 the draft tube with a surrounding chamber which will be of such extent as to allow in the water smooth flow lines of considerable radius to most efficiently let the water flow, partly above and partly below the tail water level while it is in the discharge chamber.

Another object of the invention is to provide 40 the discharge chamber with an additional cross-section above the tail water level 45 to pass the water issuing from the upstream portion of the draft tube whereby the depth of the excavation below the tail water level is reduced. Since any water that can be discharged without a loss of efficiency 50 through the discharge chamber above the tail water level reduces by precisely that extent of chamber the necessity for excavation lower than the tail water level.

The depth of the draft tube is ordinarily 55 dependent upon the difference in elevation between the base of the turbine and the con-

venient depth below the tail water level up to a limit of the depth required to balance the atmospheric pressure and the angle of the draft tube due to its increasing area 60 downwardly and then upwardly is that angle which will give as slow a discharge movement to the water as possible without danger of breaking the vacuum either in the vacuum chamber or in the draft tube. 65

Other objects of the invention will appear as the description proceeds.

An embodiment of the invention is shown in the accompanying drawings in which the same reference numeral is applied to the 70 same portion throughout, but I am aware that there may be modifications thereof.

Figure 1 is a vertical sectional view of a turbine with a thin walled draft tube discharging into the vacuum chamber. 75

Figure 2 is a vertical section at right angles to Figure 1, the turbine being omitted.

Figure 3 is a horizontal cross-section on line 3—3, Figure 1. 80

Figure 4 is a vertical section at a slightly different form of draft tube and vacuum chamber.

Figure 5 is a vertical section of the tube and chamber at right angles to Figure 4. 85

Figure 6 is a sectional plan view of a portion of the draft tube and vacuum chamber of Figure 4 on the line 6—6.

Figure 7 is a vertical sectional view of a turbine draft tube and discharge chamber of 90 a slightly different form.

Figure 8 is a vertical sectional view of a portion of the draft tube and discharge chamber of Figure 7 looking toward the outlet, and Figure 9 is a plan on the section line 9—9, Figure 7. 95

In Figure 1 the numeral 1 indicates the turbine, 2 the penstock wall and 3 the draft tube, which tube is small where it leaves the turbine and larger at its lower end, the exact angle of the cone being determined by well known conditions of hydraulics unnecessary to consider here. The draft tube discharges into a large chamber V' open for its full width at the front to the tail race and which has a curtain wall 5 extending below the level of the surface of the tail race water. As the tube 3 is made of a comparatively thin material the cross-sectional area of the water passages increase constantly downwardly from the turbine and then upwardly from the bottom of the draft 105 110

tube 3. As the height of the water discharge chamber V' is considerable that portion of the chamber above the level of the tail water will always be subjected to a pressure below atmospheric, and to prevent the accumulation of air from the water in the chamber there is a vacuum pipe 6 leading from the chamber to a suitable vacuum pump which may be operated occasionally.

10 In the form of the invention shown in Figures 4 to 6 the draft tube is cast in concrete and has its lower end smoothly rounded as shown at 7, while to increase the discharge area from the upstream side the tube walls are made thinner and the shoulders 8, 9 are produced on the sides of the draft tube. The vacuum chamber V^2 is smoothly curved throughout and has its discharge opening 10 inclining downwardly so the wall 11 is below the water surface of the tail race.

15 In the form of the invention shown in Figure 7 the turbine is indicated at 20, the tube 21 is cast in concrete. The discharge or 25 vacuum chamber V^3 is formed on a flat surface 22 which extends to the tail race with the curtain wall 23 below the surface of the water in the tail race. In this form of the invention the draft tube has its side walls thinned to produce shoulders 24 25 to increase the discharge areas.

20 Both of the latter forms of the invention may be provided with the vacuum pipe 6 to remove any air collecting in the vacuum chamber.

25 The vacuum pipe 6 must of necessity be operated at the starting of the turbine to produce the desired vacuum in the vacuum chamber, but thereafter it need only be operated occasionally as air may collect therein.

30 What I claim is as follows, but various modifications may be made in the construction shown in the drawings and above particularly described form, within the purview 40 of my invention:

45 1. The combination with a turbine of a downward flow draft tube and a water

sealed vacuum chamber into which the draft tube discharges.

2. The combination with a turbine having 50 a downward flow draft tube of a chamber larger in area than the draft tube, said chamber having a curtain wall below the level of the water in the tail race.

3. The combination with a turbine having 55 a downward flow draft tube of a vacuum chamber into which said tube extends, the discharge area of said chamber increasing upwardly for a portion of its height.

4. The combination with a turbine having 60 a downwardly extending draft tube of a vacuum chamber, and means to exhaust the air from said chamber whenever necessary.

5. The combination with a turbine having 65 a downwardly extending draft tube increasing in diameter downwardly of a vacuum chamber having a curtain wall extending below the level of the water in the tail race into which the draft tube extends, and means to exhaust the air from the vacuum chamber 70 whenever necessary.

6. The combination with a turbine and its draft tube of a vacuum chamber extending above the level of the bottom of the draft tube.

7. The combination with a turbine having 75 a downwardly extending draft tube of a vacuum chamber extending above the level of the bottom of the draft tube, the discharge area of said chamber being greater 80 at an intermediate point than at the bottom.

8. The combination with a turbine and a downwardly extending draft tube of a vacuum chamber, said chamber extending upwardly from the bottom of the draft tube 85 and being of increasing cross-sectional area from its lower portion to an intermediate portion thereof, and means to exhaust the air from said chamber when necessary.

90 In testimony whereof I have hereunto set my hand this 10th day of July, A. D. 1922.

OSCAR C. GOERIZ.
